UNITED STATES PATENT OFFICE.

LERoy ATKINS, OF TRENTON, MISSOURI.

GRAIN-STEAMER.

SPECIFICATION forming part of Letters Patent No. 408,682, dated August 13, 1889.

Application filed August 5, 1887. Renewed March 18, 1889. Serial No. 303,822. (No model.)

To all whom it may concern:

Be it known that I, LEROY ATKINS, a citizen of the United States, residing at Trenton, in the county of Grundy and State of Missouri, have invented certain new and useful Improvements in Grain-Steamers; and I do hereby declare the following to be a full, clear, and exact description of the invention, such as will enable others skilled in the art to which it appertains to make and use the same.

This invention relates to grain-steamers, and has for its object the construction of a cheap, simple, and effective device for steaming grain while on its way to the grinding mill or rollers.

The invention will be hereinafter described, and particularly pointed out in the claim.

In the accompanying drawings, which form a part of this specification, Figure 1 is a perspective, partly broken away; Fig. 2, a vertical longitudinal section, and Fig. 3 a transverse section on the line 3 3 of Fig. 2.

Reference being had to the drawings and the letters marked thereon, A represents a grain-steamer, which is divided into an upper chamber or passage-way *a*, for grain to pass through, and a lower chamber *b*, into which steam enters, and the water of condensation produced by the steam is collected and conducted away. The two chambers are separated by a horizontal foraminous partition *c*, of wire-gauze, which is secured to side ledges *d* (only one of which is shown) and to the end ledges *e f* by solder, or in any other suitable manner. The ledge *e* at the lower end of the steamer projects in a considerable distance farther than the ledge *f* at the opposite end, extends beyond the ends of the tubes *g h*, and forms a baffle-plate for the steam issuing from the tube *g* and directs it along the under side of the wire-gauze partition *c*, through which the steam passes, and completely surrounds the grain passing through the chamber or passage *a*. The water of condensation is conducted from the chamber *b* through the tube *h*, and to prevent any water entering the pipe *g*, through which the steam is supplied, it (the tube) projects above the bottom 50 of the chamber *b*, as shown at *i*. At the lower

end of the steamer A, and on both sides thereof, are trunnions B B, which are mounted in bearings *k k* in the brackets or supports C C, for the purpose of changing the angle of inclination of the steamer to cause the grain 55 to pass through the chamber *a* at different rates of speed, according to the capacity of the mill or rollers used to grind or roll the grain and the condition of the grain.

The steamer is located at any convenient 60 place between the stock-hopper and the last cleaner, or between the stock-hopper and the rollers, and its free end may be raised or lowered and secured in any convenient and suitable manner.

By my construction grain may be thoroughly steamed without being exposed to the water of condensation and all the desirable and beneficial results of the steaming obtained without subjecting the grain to any of the 70 deleterious effects usually produced by the water of condensation coming in contact therewith.

The steamer may be made of wood or metal, and may be of rectangular form, as shown, or 75 it may be cylindrical or of any other form. That shown is, however, preferred, for the reason that the grain is spread out over a greater surface and can be kept running in a thinner stratum than in most other forms.

Having thus fully described my invention, what I claim is—

In a grain-steamer, a grain-chamber open at both ends, a steam-chamber under the grain-chamber, and a horizontal foraminous partition between said chambers, in combination with a steam-supply pipe and a pipe for conducting water of condensation from the steam-chamber, both of said pipes being at one end of the steamer, and a baffle-plate in the plane 85 of the foraminous partition and constructed to direct steam along the under side of said partition, substantially as described.

In testimony whereof I affix my signature in presence of two witnesses.

LERoy ATKINS.
